UNITED STATES PATENT OFFICE.

WILLIAM H. WILKINSON, OF ROCHESTER, NEW YORK, ASSIGNOR TO THE CO-OPERATIVE FOUNDRY COMPANY, OF SAME PLACE.

DESIGN FOR A HEATING-STOVE.

SPECIFICATION forming part of Design No. 20,946, dated July 14, 1891.

Application filed June 10, 1891. Serial No. 395,816. Term of patent 7 years.

To all whom it may concern:

Be it known that I, WILLIAM H. WILKINSON, of Rochester, in the county of Monroe and State of New York, have invented and 5 Produced a new and original Design for Heating-Stoves, of which the following is a specification, reference being had to the accompanying photograph, forming a part thereof.

The photograph shows a perspective view 10 of a stove constructed in accordance with my design.

The leading features of my design consist 15 of the peculiar shape and surface ornamentation of the stove as a whole and also of the shape and ornamentation of the separate sections hereinafter described.

The stove may, for convenience of description 20 of the design, be divided into several sections, viz: the base 1, the ash-pit 2, the body 3, and the top 4.

The base-section is composed of two parts, 25 the lower one rounded and provided with the more or less indented and curved lower edge and the ornaments 6, extending from near the upper sides of the legs toward the center of the sides, and the slightly-curved ribs 7 at the extreme corners, intersected by a band 8.

The upper part 9 of the base-section is also 30 curved and rounded, its lower edge resting on top of part 5 and its upper part joining the lower part of the ash-pit section and provided with suitable surface ornamentations, such as shown, consisting of curved and involute lines and sprays.

35 The ash-pit section is of substantial ogee or reverse curved shape, having the ornamental panels 10 on the sides and the ash-pit door 11 at the front, which is provided with the usual damper openings. Between the 40 ash-pit and body sections is a depending flange or apron 12, ornamented as shown, and to this on opposite sides are secured the foot-rest plates 13, rounded and provided with the ornamental sprays, ribs, and involutes thereon, and with the upwardly-extending arms 14 resting upon and secured to the flange 12.

The body-section is divided at the corners by vertical beaded columns 10, provided with 45 projections or reversed brackets 15, and is divided horizontally by beads or bands 16, the

front portion of the lower horizontal section having double doors 17, provided with the cross-bars and spray-ribs 18, and the side door 19, ornamented by the cross-bars and sprays 20. Above the horizontal bands the body is 55 provided with the doors 21 at the front, having the cross-bars and sprays thereon, and the rosettes 22, and at the sides are provided doors 23, ornamented with the ribs, sprays, and central rosettes 24. At the back of the body-section is provided a swelling bracket or shelf 60 32, suitably ornamented.

The top section 4 is provided with depending corner portions 25, joining the tops of the vertical column 14 of the body, and from the 65 horizontal band 26 is rounded inward and down to these, and is also curved inward or recessed where the walls are joined by curved panels 27 of open-work ribs and sprays. The interiors of these recessed portions are 70 ornamented by ribs and sprays, and at the corners over the columns 14 are rosettes 28. The top above the band 26 is rounded over and ornamented by the lines, sprays, and involutes, and from the center rises the dome or lid 29, also 75 ornamented by the sprays, &c., and upon this lid is a small statuette or ornament 30, in the present instance representing a knight on horseback; but this figure may be changed without altering the leading features of the 80 design.

What I claim as my invention is—

1. In a design for stoves substantially as shown, the herein-described design for the stove-base section, consisting of the two superposed sections arranged and ornamented, as set forth.

2. In a design for stoves substantially as shown, the herein-described design for the ash-pit section reversely curved, as shown, having 90 the ornamental panels at the sides and the door at the front provided with the openings and the flange or apron 12, as set forth.

3. In a design for stoves substantially as shown, the herein-described design for the depending flange or apron 12 and the plates 13, ornamented as shown and having the upwardly-extending arms engaging the flange 12, as set forth.

4. In a design for stoves substantially as 100

shown, the herein-described design for the body-section embodying the vertical columns having the reversely-curved projections, the horizontal ribs, and the several doors or panels provided with ribs and sprays, as set forth.

5. In a design for stoves substantially as shown, the herein-described design for the top section having the recessed portions at the top and sides and the panels 27, of open-work ribs and sprays, the band 26, the rounded up-

per portion, and the lid or dome 29, as set forth.

6. The herein-described design for stoves, substantially as shown in the accompanying drawings.

WILLIAM H. WILKINSON.
